RAZOR

James L. Younghusband, Chicago, Ill.

Application August 18, 1941, Serial No. 407,281

1 Claim. (Cl. 30—70)

This invention relates to a razor adapted to prevent blade rust. Among the objects of my invention is to construct a razor of the safety type so that when the razor is not in closed operating position, that blades will be spaced from contact with the head and guard. Another object is to provide automatic resilient means which will move the blade away from contact with the head and guard when the razor is in open position and recesses for housing the resilient means when the razor is in closed shaving position. My invention also contemplates such other objects, advantages and capabilities as will later more fully appear and which are inherently possessed by my invention.

While I have shown in the accompanying drawing a preferred form of my invention, yet I desire it understood that the same is susceptible of modification and change without departing from the spirit of my invention.

Referring to the drawing, Fig. 1 is a top plan view of my razor; Fig. 2 is a side elevation of the same in closed position and Fig. 3 is a detailed sectional view on line 3—3 of Fig. 1 of the same in open position.

Referring now more particularly to the embodiment selected to illustrate my invention, it comprises a head 10 having a depending screw threaded shank 11, a guard 12 having an opening 13 adapted to receive shank 11 when the razor is assembled, and handle 14 having a screw threaded aperture 15 adapted to engage the screw threads of shank 11.

A resilient member or spring 16 is preferably centrally attached to the inner portion 17 of the head 10. A recess 18 is also provided in the bulge 60 of the inner portion 17 to accommodate resilient member 16.

Another resilient member 19 is preferably centrally attached to the inner portion 20 of guard 12. A recess 21 is also provided in well 61 of the inner portion 20 to accommodate resilient member 19. In use, when a blade 22 is placed between head 10 and guard 12 and the handle 14 is turned until the blade 22 is contacting the head 10 with one of its surfaces and the guard 12 with its other surface, resilient member 16 is moved into recess 18 and resilient member 19 is moved into recess 21. The recesses thus accommodate the springs and permit normal closing of the razor for shaving purposes.

After the shaving operation is over, the razor is, of course, wet. If the razor is left in closed position, water will be held between the blade and the head on one side and the guard on the

other side. In this condition the blade will acquire rust spots, resulting in early deterioration of the blade, and creating a plurality of rough, broken, jagged edges which are likely to tear and stab the shaver in the next operation instead of the smooth cut necessary for shaving.

When the ordinary razor is loosened, the blade moves against either the head or the blade and the rusting by wet contact continues.

10 The only way to prevent this with the ordinary razor is to disassemble the head, guard, blade and handle and dry with a cloth. This is annoying and dangerous.

With my razor, disassembly and drying with a 15 cloth after shaving are unnecessary. The handle is slightly turned so that spring 16 automatically moving inwardly from recess 18 in head 10 pushes the blade 22 away from contact with the head 10. At the same time spring 19 automatically moving inwardly from the recess 21 in guard 12 pushes the blade 22 away from contact with the guard 12. Thus the blade is spaced from contact with either head 10, or guard 12. No water can be held suspended between the parts 20 for rusting the blade. Evaporation will dry the blade 22 before there is rust. If the blade is rinsed in hot water and excess water shaken off, the drying will be almost immediate. The life of blades and their maximum shaving efficiency is 25 greatly increased.

Having thus described my invention, I claim:

A razor comprising a head having a depending screw threaded shank, a guard having an opening to permit said shank to pass therethrough, said head and said guard adapted to hold a blade therebetween, a handle having a screw threaded aperture to engage said screw threaded shank, so that upon said handle being turned in one direction said guard is moved into 35 closed shaving position against said blade and upon said handle being turned in the opposite direction said guard is moved away from said head, said head having on its inner portion a centrally disposed recess, a spring attached to 40 said head within said recess, said guard having on its inner portion a centrally disposed recess, a spring attached to said guard within said recess and positioned opposite to the spring in the recess of said head, said springs directly 45 contacting opposite sides of the blade, said springs of substantially similar size and normally extending outwardly from their respective recesses and toward each other, said springs adapted to be compressed by said head and said guard 50 upon the handle being turned in one direction

to move said head and said guard into closed shaving position, said recesses of sufficient size to accommodate their respective compressed springs and permit said head and said guard to contact the blade, said springs adapted upon said handle being turned in the opposite direction to move said guard and said head away from closed shaving position, to exert substantially

similar pressure on the respective opposite sides of the blade to move the blade away from contact with said head and said guard, and to maintain the blade in spaced position between said head and said guard, the edges of said blade remaining flat and unflexed at all times by said springs.

JAMES L. YOUNGHUSBAND.
